UNITED STATES PATENT OFFICE

ALFRED G. LEGGE, OF BROCKTON, MASSACHUSETTS

SHOE FORM

Application filed March 5, 1932. Serial No. 596,968.

This invention relates to shoe forms adapted for use in ladies' shoes to support a strap connecting points on opposite sides of the shoe upper intermediate the toe and heel of the shoe.

It is an object of the present invention to provide an improved form adapted to fill out the upper of such a shoe and at the same time support the strap in substantially the position it would assume upon the foot of the wearer.

The invention will be more clearly understood from the following description in conjunction with the accompanying drawing: in which,

Fig. 1 is a sectional elevational view of a shoe in which is positioned a form embodying the invention;

Fig. 2 is a view of a shoe similar to that of Fig. 1 in which is positioned another form embodying the invention;

Figs. 3 and 4 are views of the forms shown in Figs. 1 and 2 respectively looking at the bottom of the form; and

Fig. 5 is an enlarged sectional view taken upon the line 5—5 of Fig. 1.

In Fig. 1 a lady's shoe 10 is shown having a strap 11 connecting points on opposite sides of the upper 12 intermediate the toe and heel parts of the shoe. A form embodying the invention is positioned within the shoe 10 and comprises a hollow toe part 15 of sheet celluloid or the like provided with a bottom in-turned flange 16 and having flexible or relatively movable side portions 17. The flexible side portions 17 are connected by a toggle comprising links 18 pivotally connected at one end by a rivet 19 and pivotally secured at their other ends to the portions of the in-turned flange 16 adjacent the flexible side portions 17, as by rivets 20. A member 21 is pivotally connected at its rear end to the rivet 19 and extends forwardly from the toggle so that its forward end may extend over the flange 16 and engage the interior of the tip of the toe part 15. A flexible member 22 is connected at its forward end to the forward portion of the member 21, as by a rivet 23, and extends rearwardly from within the toe part 15 and is of such a length as

to engage the heel portion 24 of the shoe substantially from the top to the bottom thereof, whereby the member 22 is bulged upwardly and forwardly so as to engage the strap 11. Preferably, the member 22 comprises a channel or U-shape member 25 of sheet celluloid in which a flexible metallic wire 26 is positioned and secured at its ends to the ends of the channel member 25 as by a rivet 27 and the rivet 23.

When the form is to be inserted in a shoe the toggle is collapsed so as to contract the flexible side portions 17, as shown in full lines in Fig. 3. When the toe part 15 has been inserted into the toe part of the shoe the rear end of the flexible member 22 is placed against the heel portion 24 of the shoe causing the member to bulge upwardly and forwardly into engagement with the strap 11 and at the same time expanding the toggle to move the flexible side portion 17 snugly into engagement with the toe part of the shoe upper. In so doing the forward end of the member 21 is brought into engagement with the tip of the toe part 15 so as to limit the forward movement thereof.

The construction illustrated in Figs. 2 and 4 is similar in most respects to that illustrated in Figs. 1 and 3. In this construction the member 21' is pivotally connected at its rear end to the toggle by the rivet 19' which pivotally connects adjacent ends of the links 18'. The member 22' is formed as an integral part of the member 21' and extends from the forward end thereof. The member 22' is in the form of a thin strip of metal and is of such a length as to engage the heel portion 24' of the shoe 10' substantially from its bottom to its top and to rest snugly against the strap 11'. The rear end of the member 21' is provided with a downwardly bent portion 28 adapted to engage the rear edge of the toggle links 18' and thus limit the forward movement of the member 21' due to the urge of the member 22'.

What I claim is:

1. In a shoe form, the combination of a flexible toe part having an inwardly extending flange at the bottom thereof, a toggle connecting the opposite side portions of said

flange, a member operatively connected with said toggle and extending rearwardly from within said toe part, said member being flexible and of such length as to permit its free 5 end portion to engage substantially from the top to the bottom of the heel portion of the upper of a shoe in which the form is placed whereby the intermediate portion of said member is caused to bulge upwardly and 10 forwardly to engage a cross strap of the shoe.

2. In a shoe form, the combination of a hollow toe part having an inwardly extending flange at the bottom thereof, a member secured to said toe part within the same and extending rearwardly therefrom, said member being flexible and of such length as to engage substantially from the top to the bottom of the heel portion of the upper of a shoe in which the form is placed whereby said member 15 is caused to bulge upwardly and forwardly to engage a cross strap of the shoe, said member comprising a strip of sheet celluloid of substantially U-shape enclosing a flexible metallic wire to which it is secured at its 20 ends.

3. In a shoe form, the combination of a flexible toe part having an inwardly extending flange at the bottom thereof, a toggle connecting the opposite side portions of said 25 flange, a member operatively connected with

said toggle and extending rearwardly from within said toe part, said member being flexible and of such length as to engage substantially from the top to the bottom of the heel portion of the upper of a shoe in which the form is placed whereby said member is caused to bulge upwardly and forwardly to engage a cross strap of the shoe, and means for limiting the forward movement of the operative connection between said member and toggle. 75

4. In a shoe form, the combination of a hollow flexible toe part having an inwardly extending flange at the bottom thereof, a toggle connecting the opposite side portions of said flange, a connection with said toggle extending forwardly therefrom into said toe part, a member extending rearwardly from said connection, said member being flexible and of such length as to engage substantially from the bottom to the top of the heel portion of the upper of a shoe in which the form is placed whereby said member is caused to bulge upwardly and forwardly to engage a cross strap of the shoe, said connection having an inwardly bent rear end adapted to engage 85 said toggle. 90

In testimony whereof I affix my signature.

ALFRED G. LEGGE.
